DENTAL PLATE

Royal S. Hagerman, Vilas, Colo.

Application February 23, 1940, Serial No. 320,505

7 Claims. (Cl. 32—2)

This invention pertains to artificial dental construction and especially to dental plates.

The users or the wearers of artificial dental constructions are frequently troubled with the dentures accidentally falling or being blown out of the mouth. This is especially true in the case of plates in which event the wearer lacks natural teeth which can be used as a foundation for the artificial dentures. It is, furthermore, especially true in the case of lower plates because the upper plates under conventional practice can be constructed to adhere to the palate of the mouth. The tongue structure prevents such adhesive holding of lower plates.

In the practical application of my invention I make use of the side surfaces of the jaw bone of the wearer as a gripping surface for the dental construction, and I provide the base member in which the artificial teeth are mounted with areas which overlap the side surfaces of the jaw bone. I constructed the plate in such a manner that these overlapping areas are yieldingly pressed toward the side surfaces of the jaw bone.

The entire plate is made of uni-structure of yielding and non-yielding material and I mold the structure to space the side portions a different distance apart than the distance between the side portions of the jaw bone of the wearer. The structure must be distorted to insert the plate in the mouth, the yielding portion permitting such distortion. I also render the yielding portion resilient in a manner to cause the overlapped portions to press against the jaw bone of the wearer.

The position of the yielding portion in the dental structure may be varied without departing from the spirit of the invention.

Having stated the invention generally, attention is now directed to the drawing in which:

Figure 1 is a perspective view of one embodiment of the invention;

Figure 2 is a plan view of the embodiment of Figure 1, with parts broken away;

Figure 3 is a horizontal cross section of a modified form of the embodiment shown in Figure 2;

Figure 4 is a perspective view of another embodiment of the invention;

Figure 5 is a vertical section of a modified form of the embodiment shown in Figure 4; and

Figure 6 is a section taken on line 6—6 of Figure 5.

The specific embodiment shown in the drawings illustrates the invention as applied to lower plates. The invention may also be applied to

upper plates without departing from the spirit of the invention.

As illustrated most clearly in Figures 1 and 4, the lower plate consists of artificial dentures 7 mounted in the supporting base 8. The supporting base comprises a front portion shown generally at 9 and two side portions 10 and 11 extending rearwardly therefrom on both sides of the lower jaw.

10 The supporting base 8 as in conventional practice is preferably made of rubber although other materials have been and may be used. In the practice of the invention it consists of non-yielding portions 12 with portions 14 of yielding material in the nature of inserts. The portions 14 are not inserts in the strictest sense of the term because they are molded unitary with the portions 12 to provide an integral uni-structure.

15 In practice the non-yielding and yielding portions 12 and 14 comprise hard and soft rubber respectively in the preferred embodiment of the invention.

20 The dental plate constructed as described is molded to fit the top and side surfaces of the gums wherever it is in engagement therewith, but is molded to provide a distance between the side members 10 and 11 which is different than the distance between the side members of the jaw bone of the wearer. In the instant case

25 since the pressure is to be applied to the inside surfaces of the jaw bone the members 10 and 11 are spaced a greater distance apart than the sides of the jaw bone. Projecting downwardly from the side portions 10 and 11 are the overlapped

30 areas 15 and they extend far enough to be juxtaposed to the inside surfaces of the side portions of the jaw bone. Usually, this portion of the jaw bone is undercut and affords a good holding surface for lower plates. Thus, the 35 overlaps 15 are shaped in a manner shown in Figure 6.

35 In the case where the yielding material 14 is soft rubber, it is also resilient and tends to maintain the plate to the shape to which it is molded.

40 Thus, when the plate is distorted to be inserted in the mouth of the wearer pressure will be exerted outwardly laterally to compress the overlaps 15 against the side surfaces of the jaw bone.

45 If greater resiliency is desired or required the modification of Figure 3 can be used. This comprises a spring member 16 embedded in the yielding material 14' and entirely embedded in the tooth supporting structures of the plate. The spring member 16 extends into the non-yielding material preferably in both directions as at 17.

This modification permits the plate to be used in the manner hereinbefore described.

In the second embodiment of my invention disclosed in Figures 4, 5 and 6, I make the overlaps 15' of yielding material molded uni-structure with the non-yielding material. In this embodiment, preferably, the non-yielding material extends throughout the front and side portions 9', 10', 11' to the supporting base 8'.

In this embodiment the overlaps 15' are molded to be a greater distance apart than the distance between the side portions of the jaw bone so that when the plate is inserted in the mouth, they exert a lateral pressure against the side surfaces of the jaw bone. They thus accomplish a result similar to that described with reference to the embodiment of Figure 1.

In the modification of this embodiment shown in Figures 5 and 6, I provide the spring member 16' which is embedded in the yielding material at 18' and extends into the non-yielding material as at 17'. The spring member gives resiliency to the overlaps 15' which function in the manner hereinbefore described.

Having thus described my invention in detail, I do not wish to be limited to the specific structure shown and described but the scope of the invention as measured by the accompanying claims.

What I claim is:

1. An artificial dental construction comprising dentures and a supporting base for the dentures, the supporting base consisting of uni-structure, non-yielding and yielding material molded to fit the surface of the gums, the base comprising a front portion and two side portions extending rearwardly therefrom on both sides of the jaw, each with an overlapping area alongside the jaw bone, the base being molded to space the overlapping areas a different distance apart than the spacing between side portions of the jaw bone of the wearer, the yielding material being resilient to press the overlapping areas toward the side surfaces of the jaw bone when distorted from the shape to which they are molded to the position they occupy in the mouth.

2. An artificial dental construction comprising dentures and a supporting base for the dentures, the supporting base consisting of uni-structure, non-yielding and yielding material molded to fit the surface of the gums, the base comprising a front portion and two side portions extending rearwardly therefrom on both sides of the jaw, each with an overlapping area alongside the jaw bone, the base being molded to space the side portion a different distance apart than the spacing of the side portions of the jaw bone of the wearer, the yielding material tending to maintain the base to the shape to which it is molded and being resilient to press the side portions laterally with the overlapping areas urged toward the side surfaces of the jaw bone when the base is distorted from the shape to which it is molded to the position it occupies in the mouth.

3. An artificial dental construction comprising dentures and a supporting base for the dentures, the supporting base consisting of uni-structure, non-yielding and yielding material molded to fit the surface of the gums, the base comprising a front portion and two side portions, the front portion including the yielding material, the side portions extending rearwardly from the front portion on both sides of the jaw each with an overlapping area alongside the jaw bone, the

base being molded to space the side portions a different distance apart than the spacing between side portions of the jaw bone of the wearer, the yielding material being resilient tending to maintain the plate to the shape to which it is molded to press the side portions laterally with the overlapping areas urged toward the side surfaces of the jaw bone when the plate is distorted from the shape to which it is molded to the position it occupies in the mouth.

4. An artificial dental construction comprising dentures and a supporting base for the dentures, the supporting base consisting of uni-structure, non-yielding and yielding material molded to fit the surface of the gums, the base comprising a front portion and two side portions extending rearwardly therefrom on both sides of the jaw bone, each with an overlap area of yielding material alongside the jaw bone, the base being molded with the overlaps spaced a different distance apart than the spacing between the side portions of the jaw bone of the wearer, the yielding material of the overlaps being resilient to press them laterally toward the side surfaces of the jaw bone when they are distorted from the shape to which they are molded to the positions they occupy in the mouth.

5. An artificial dental construction comprising dentures and a supporting base for the dentures, the supporting base consisting of uni-structure, non-yielding and yielding material molded to fit the surface of the gums, the base comprising a front portion and two side portions extending rearwardly therefrom on both sides of the jaw, each with an overlapping area alongside the jaw bone, the base being molded to space the side portions a different distance apart than the spacing between side portions of the jaw bone of the wearer, a spring member embedded in the material of the base and extending into both the yielding and non-yielding material to supply resilience to the yielding material tending to maintain the base to the shape to which it is molded to press the side portions laterally with overlapping areas urged toward the side surfaces of the jaw bone when the base is distorted from the shape to which it is molded to the position it occupies in the mouth.

6. An artificial dental construction comprising dentures and a supporting base for the dentures, the supporting base consisting of uni-structure, non-yielding and yielding material molded to fit the surface of the gums, the base comprising a front portion and two side portions, the front portion including the yielding material, the side portions extending rearwardly from the front portion on both sides of the jaw each with an overlapping area alongside the jaw bone, the base being molded to space the side portions a different distance apart than the spacing between side portions of the jaw bone of the wearer, a spring member embedded in the yielding material and extending into the non-yielding material in opposite directions to supply resilience to the base tending to maintain it to the shape to which it is molded to press the side portions laterally with the overlapping areas urged toward the side surfaces of the jaw bone when the plate is distorted from the shape to which it is molded to the position it occupies in the mouth.

7. An artificial dental construction comprising dentures and a supporting base for the dentures, the supporting base consisting of uni-structure, non-yielding and yielding material

molded to fit the surface of the gums, the base comprising a front portion and two side portions extending rearwardly therefrom on both sides of the jaw bone, each with an overlap area of yielding material alongside the jaw bone, the base being molded with the overlaps spaced a different distance apart than the spacing between the side portions of the jaw bone of the wearer, a spring

member embedded in the yielding material and extending into the non-yielding material to give resilience to the overlaps to press them laterally toward the side surfaces of the jaw bone when they are distorted from the shape to which they are molded to the positions they occupy in the mouth.
